(57) **CLAIM**

The ornamental design for a skylight outer frame, as shown and described.

DESCRIPTION

FIG. 1 is a perspective view of the skylight outer frame; FIG. 2 is an end elevation view of the skylight outer frame; and,

FIG. 3 is an end elevation view of the skylight outer frame shown in a condition of use with unclaimed environment shown in broken lines.

FIGS. 1 and 3 disclose a symbolic break. The portions beyond the break form no part of the claimed design. The evenly spaced dash-dash broken lines depict environment that forms no part of the claimed design.
